BOBBIN DRAG DEVICE FOR SPINNING AND
LIKE TEXTILE FRAMESGordon Fraser, Norman Fraser, and John Fraser,
Arbroath, ScotlandApplication November 22, 1934, Serial No. 754,240
In Great Britain May 27, 1933

3 Claims. (Cl. 118—55)

This invention relates to bobbin drag devices for spinning and like textile frames and has for an object to provide a construction in which the overhang of the bobbin spindle is reduced to a minimum.

5 The device according to the invention comprises a plurality of concentric rings including a fixed inner drag ring surrounded by supplementary rings axially movable independently of one another into and out of engagement with a surface or surfaces rotatable with the bobbin.

In practice, the fixed inner drag ring is constituted by a flange on the bobbin spindle.

10 The undersides of the movable rings, namely an outer ring and an intermediate ring, are formed with inclined surfaces engageable by projections on a base plate so arranged that relative angular movement of said movable rings and said base plate is accompanied by axial displacement of said movable rings.

15 The intermediate and outer rings of the drag may be angularly adjusted and are so relatively disposed with respect to their inclined surfaces and to the projections on the base plate that angular adjustment of said rings in one direction causes said rings to rise one after the other, and, conversely, angular adjustment of said rings in the opposite direction causes them to descend one after the other.

20 30 A bobbin drag device according to the invention is illustrated in the accompanying drawings in which Fig. 1 is a vertical section, Figs. 2 and 2a fragmentary plan views, and Fig. 3 a fragmentary detail elevation. Fig. 4 is a fragmentary vertical section.

35 The device shown comprises three concentric rings 1, 2 and 3, respectively, including an inner drag ring 1 constituted by a flange on the bobbin spindle socket 4, an angularly adjustable and axially movable intermediate ring 2 embracing the ring 1, and an outer angularly adjustable ring embracing the intermediate ring 2, and axially movable independently of said intermediate ring 2.

40 45 Also embracing the ring 1 is a stationary annular base plate 5 formed with upwardly projecting ridges 6 engageable with inclined surfaces 7 on the undersides of the intermediate and outer rings 2, 3.

50 The outer rings 3 of the drag arrangements for a plurality of bobbins are angularly adjusted by actuation of a common slide bar 8 disposed alongside said rings and operatively connected to the outer rings 3, the bar 8 being provided with pins 55 9 each engageable with a notch 10 in the underside of a ring 3.

55 60 Each outer ring carries a horizontal pin 3' projecting into a slot 2' in the intermediate ring 2, so that the final stage of circular movement imparted to the outer ring 3 is communicated to

the intermediate ring 2. The pin and slot engagement allows axial movement of the outer ring relatively to the intermediate ring.

11 denotes a spindle secured at its lower end in the socket 4.

5 Journalled on the spindle 11 is a spindle tube 12 to which is attached a bobbin-driving platform 13 to the underside of which is fixed a disc 14 of felt or other frictional material engageable by the upper annular surfaces of the rings 1, 2 and 3.

10 15 In operation, drag can be applied in one, two, three or more stages, depending on whether the disc 14 is bearing only on the inner ring 1, or on the intermediate ring 2 or on the outer ring 3, the rings 2 and 3 being successively raised to operative or dragging position by the traverse of the inclined surfaces 7 across the ridges 6 on the base plate 5.

20 The driving platform 13 may be of aluminium or light metal or it may be of cast iron or other heavy metal for higher ranges.

25 The base plate 5 is held against rotation by means of a pin 15 carried by said plate 5 and engaging a socket 16 in the bobbin lifter rail 17.

18 denotes a bobbin impaled on the spindle tube 12, sockets 19 in the base flange of the bobbin 18 being engaged by driving pegs 20 upstanding from the driving platform 13.

30 We claim:—

1. A bobbin drag device for spinning and like textile frames comprising, a platform rotatable with the bobbin and presenting a friction surface, a bobbin spindle, a fixed drag ring in engagement with said friction surface, and supplementary drag rings concentric with said fixed ring, said supplementary rings being movable independently of one another into and out of engagement with said friction surface.

35 40 2. A bobbin drag device as claimed in claim 1 in which the fixed drag ring is constituted by a flange on the bobbin spindle socket.

45 3. A bobbin drag device for spinning and like textile frames comprising a platform rotatable with the bobbin and presenting a friction surface, a bobbin spindle, a fixed drag ring, supplementary drag rings concentric with said fixed ring, a base plate concentric with said rings and having projections on one surface thereof, the supplementary drag rings having inclined surfaces adapted to engage said projections, and means for causing relative angular movement of said supplementary drag rings and said base plate to bring about axial displacement of said supplementary drag rings to cause same to engage with 50 or to be disengaged from said friction surface.

55 GORDON FRASER.
NORMAN FRASER.
